HARRY L. GUY, OF CHICAGO, ILLINOIS, ASSIGNOR OF ONE-HALF TO HOMER J. LUCE,
OF CHICAGO, ILLINOIS

ROOFING

Application filed June 19, 1931. Serial No. 545,391.

This invention relates to lock shingles, and among other objects aims to provide interlocking ornamental shingles which may be produced without waste.

5 The invention may be readily understood by reference to an illustrative construction embodying the invention and illustrated in the accompanying drawings.

In said drawings:

10 Fig. 1 is a plan view of a roof surface formed with interlocked ornamental shingle units;

15 Fig. 2 is a plan view, somewhat diagrammatic in character, illustrating the relative arrangement of the shingle units in which they may be cut without waste from sheet roofing material;

20 Fig. 3 is a perspective view, on an enlarged scale relative to Figs. 1 and 2, of the interlock between a pair of shingle units;

25 Fig. 4 is a diagrammatic view showing the interlocking principle applied to a shingle unit of conventional outline, illustrating how the same may be cut without waste from roofing material;

30 Fig. 5 is a view of the same character as Fig. 4 showing the interlock applied to a square tab shingle unit having an ornamental outline appropriate to the square tab shingle;

35 Fig. 6 is a similar view illustrating the adaptation of another strictly ornamental design to an ornamental interlocking shingle unit; and

40 Fig. 7 is a view illustrating the interlock between overlapping units of the character shown in Fig. 4.

The illustrative shingle unit is designed with a so-called ornamental outline, i. e., an outline other than the conventional or regular outlines presented by square, hexagonal, 45 triangular or diamond shapes and generally including a series of curves arranged and proportioned to present a shingle tab outline which is decorative in character. The design also incorporates interlocking means which permits interlocking of shingle units without mutilating or impairing the general effect of the design.

45 In Figs. 1, 2 and 3 there is illustrated an ornamental shingle unit 10 comprising a pair

of tabs 11 having an ornamental outline 12 comprising a series of ogee curves connected by short straight lines and proportioned to present a decorative outline. The outline of the end 13 of the tab as well as 55 the recess 14 at the base of the unit between a pair of tabs, embodies laterally projecting wings 15 and a narrower terminal portion. By making the tabs symmetrical and by arranging the design so that one half 17 thereof is merely a reversal of the other half 18, the ornamental shingle may be cut from roofing material without waste. This is illustrated in Fig. 2 wherein the material cut out to provide the space between one pair of tabs 60 65 11, forms the tab 19 of a complementary shingle unit 20. The back edges 21 and 22 of the units being straight and lying in alignment in the sheet of roofing material, a plurality of complementary units illustrated in Fig. 2, may be cut from a wide sheet of material whose width is a whole multiple of the width A of the strip from which the complementary series of shingle units are cut. As 70 here shown the ends 23 of the units lie at the 75 bases of the tabs.

In forming a roof covering from the aforesaid shingles the latter are laid in overlapping staggered courses 24, 25, 26, etc., with the tip of the tabs in one course registering 80 with the bases between the tabs of the next underlying course. Each course of shingle units is laid with the side edges or ends 23 abutting each other and thereby forming a 85 continuous ornamental outline identical with that between each shingle tab.

The shingles are interlocked by sliding the projecting ears 15 upwardly so as to underlie the portions 27 adjacent the narrow space 16 at the base of and between adjacent tabs of the 90 next underlying course. In the present case the tip 28 of the overlying tab continues the outline of the immediately adjacent portions 29 and 30 of the lower tabs and the exposed outline 31 of the overlying tab forms a continuation of the adjacent outlines 32 and 33 of such tab. Thus as shown in Fig. 1, the shingle units may be interlocked at the free ends of the tab in such a way as to harmonize with the general design and without dis- 95 100

turbing or detracting from the pleasing or decorative character of the shingle outline. No cuts or slits for interlocking purposes are necessary, no need any portion of the shingle be folded under to aid in fastening down the tabs.

Before interlocking an overlying course, nails 34 are driven through the shingles at the bases between adjacent tabs. Then the units of the next overlying course are interlocked as aforesaid. Thus the ends of the tabs of the units of each course are interlocked to a portion of the underlying course which is nailed down by an immediately adjacent nail. The entire roof covering therefore presents no free portions of shingles which may be blown up with the possibility of leakage. The depth of each shingle unit is sufficient to underlap the tabs of the second overlying course by a safe distance B. This affords ample protection in the region of the points between adjacent units in a course.

In Fig. 4 there is illustrated a shingle unit 35 comprising a pair of spaced tabs having a conventional outline to which the interlocking principle has been applied. It will be noted that the design of the interlocking and associated elements is such that the end 37 of the tab is complementary in outline to the space 38 between adjacent shingle tabs. Thus the shingles may be cut without waste from a sheet of roofing material in the manner described in connection with the shingle unit illustrated in Figs. 1 to 3. The end of each tab 37 embodies laterally projecting wings 39 and a narrower terminal portion 40 which provides the narrower recess 41 at the base of adjacent tabs under the sides of which the projecting wings 40 of the overlying shingles, lie to provide an interlock between the shingle units. The interlocked arrangement between overlapping shingles is illustrated by the shaded outline 42 which represents an overlying shingle interlocked with the underlying shingle. It will be noted that the contour 43 at the tip of each shingle tab not only forms a continuation of the outline 44 of the adjacent shingle tabs but harmonizes with the general character of such outline.

In Fig. 5 is illustrated a different form of shingle unit 45 having a pair of spaced tabs 46 whose outline is generally rectangular in character. The outline of the tabs is exactly complementary to the space 47 between adjacent tabs as is the case with the previously described designs, and embodies the laterally projecting wings 48 and the narrower terminal portion 49. In interlocking overlying courses of shingles the wings 48 of the tabs of an overlying course underlie the portions 50 adjacent the corners of the space 47 between adjacent shingles. The inset portion 51 of the tab registers with the outset edge 52 at the base between adjacent tabs. The

relative arrangement of the interlocked portions of the shingles is indicated diagrammatically by the shaded outline in this figure. It will be noted that the outline presented by the interlocked portions of the shingles contains no elements which do not fit into the general design of the unit.

In Fig. 6 there is illustrated a shingle unit 53 having a pair of shingle tabs 65 embodying a fleur-de-lis design at the ends 66 of the tabs and at the base 67 of and between adjacent tabs. It will be noted that the space between adjacent tabs is complementary to the outline of the tab and the shingles may therefore be made without waste from a sheet of roofing material. The fleur-de-lis design embodies the laterally extending wings 68 and a narrower terminal portion 69. When interlocked as illustrated at the right hand of the figure the wings 68 of an overlying shingle tab underlie the portions 70 adjacent the base of the space between adjacent tabs. The narrower terminal portion 69 in this case lies in the narrow space 71 provided by the fleur-de-lis outline, thus exposing a substantial portion of the fleur-de-lis design at the base 67. The interlocked outline generally carries out the spirit and character of the main design and does not present any unharmonious elements.

In laying each of the shingle units illustrated in Figs. 4 to 6, it will be understood that the units are nailed adjacent the bases of the spaces between adjacent tabs before the tabs of the next overlying course are interlocked, all in a manner similar to that shown in Fig. 1.

In none of the units above illustrated is the design impaired by slits or cuts employed for interlocking purposes and which do not harmonize with the general design or which impair the design when the units are interlocked. Furthermore, the interlocking of the above described shingle units does not require the folding under of any portion of the shingle unit in order to fasten down the free ends of the shingle tabs. The latter method of fastening shingles is difficult and time consuming since a portion of the shingle must be folded and placed and then nailed before the overlying course can finally be positioned.

It should be noted that the matter of avoidance of waste in the manufacture of shingles and shingle units is important, not so much from the standpoint of saving material but of avoiding small bits of material accidentally falling upon the faces of packaged shingle units and permanently staining the faces of the units. It will be understood that shingles of this character are generally made from a water-proofed so-called felt sheet coated with a heavy asphalt compound which is surfaced with a mineral coating such as crushed slate. The black asphalt compound from any bits of waste material lodging between the

shingles in the package obviously would permanently mar the face of the material. For this reason, more than any other, the production of waste is highly objectionable.

Obviously the invention is not limited to the details of the specific shingle units herein illustrated since these may be variously modified. Moreover it is not indispensable that all features of the invention be used conjointly 10 since various features may advantageously be used in different combinations and sub-combinations.

Having described my invention, I claim:

1. In a roof covering the combination comprising a plurality of overlapping courses of shingle units, each unit comprising a plurality of shingle tabs having an outline which is repeated in reversed arrangement between the tabs, whereby the space between tabs is identical in outline and size to that of a shingle tab to permit the manufacture of the shingle units without waste, said outline embodying laterally projecting wings adjacent to but spaced back from the tip of the tab and being repeated at the base of the space between adjacent tabs in a narrower space corresponding to the narrower tip of the tab and an adjacent wider space corresponding to the projecting wings, said courses of shingle units being interlocked with the wings on the tabs of one course underlying the portions of the shingles of the next underlying course adjacent said narrower space, and fastening nails driven through the underlying course adjacent said bases before the overlying units are interlocked.

2. In ornamental roofing the combination comprising a plurality of overlapping courses of shingle units, each unit comprising a plurality of shingle tabs having a decorative outline consisting of a design which is repeated in reversed arrangement between the tabs, whereby the space between tabs is identical in outline and size to that of a shingle tab to permit the manufacture of the shingle units without waste, said design embodying a rectangular outline at the end of the tab having laterally projecting wings adjacent to but spaced back from the tip of the tab and being repeated at the base of the space between adjacent tabs in a narrower space corresponding to the narrower tip of the tab and an adjacent wider space corresponding to the projecting wings, said courses of shingle units being interlocked with the wings on the tabs of one course underlying the portions of the shingles of the next underlying course adjacent said narrower space and the tips of the tabs of the overlying course lying across and closing the rectangular space at the base of the space between adjacent tabs of the underlying course, and fastening nails driven through the underlying course adjacent said bases before the overlying units are interlocked.

3. In ornamental roofing the combination comprising a plurality of overlapping courses of shingle units, each unit comprising a projecting shingle tab and an adjacent portion which serves to space the tab from the tab of the adjacent unit, the exposed edge of said unit having a decorative outline in which the outline of the end of the tab is complementary to that at the adjacent portion which forms the base of the space between adjacent tabs, said design embodying laterally projecting wings adjacent to but spaced back from the tip of the tab and being repeated at the base of the space between adjacent tabs in a narrower space corresponding to the narrower tip of the tab and an adjacent wider space corresponding to the projecting wings, said courses of shingle units being interlocked with the wings on the tabs of one course underlying the portions of the shingles of the next underlying course adjacent said narrower space and the tips of the tabs of said overlying course joining and continuing the outline at the base of the space between adjacent tabs of the underlying course, and fastening nails driven through the underlying courses adjacent said bases before the overlying units are interlocked.

4. In an ornamental roofing the combination comprising a plurality of overlapping staggered courses of shingle units, each unit comprising a projecting shingle tab and an adjacent portion which serves to space the tab and an adjacent portion which serves to space the tab from the tab of the adjacent unit, the exposed edge of said unit having a decorative outline including projecting wings spaced back from the end of the tab and a narrowed portion at the base of the space between the tabs of adjacent units which narrowed portion is of less width than the width of the tab at said wings, said units being overlapped with the wings on the tabs of an overlying course of shingles underlying the units of an underlying course at said narrowed portion to interlock the shingles of the adjacent overlying course and the tips of the tabs of the overlying course joining and continuing the outline of adjacent tabs of the underlying course.

5. A shingle unit of the character described comprising in combination a body portion having a shingle tab projecting therefrom and a laterally projecting portion adapted to space the tab from the tab of an adjacent unit, said tabs being identical in outline with the space between adjacent tabs whereby said shingle units may be formed without waste, said tab and laterally projecting portion having an ornamental outline embodying laterally projecting wings spaced back from the tip of said tab and an unbroken complementary outline for said laterally projecting portion.

6. In ornamental roofing the combination

comprising a plurality of overlapping staggered courses of shingle units, each unit comprising a projecting shingle tab and an adjacent portion which serves to space the tab from the tab of the adjacent unit, the exposed edge of said unit having a decorative outline and a rectangular tip at the end of the tab having laterally projecting interlocking wings spaced back from the ends of the rectangular tip, the outline of said tab being

repeated in inverted complementary form in the space between adjacent tabs, the wings of the tabs of an overlying course being passed through and lying beyond the portion of the outline in said space which is complementary to the wing outline, and the tips of said tabs joining and continuing the decorative outline of said space. 70
